FIG. 10.

Technical drawing of a mechanical assembly, labeled Fig. 18. The drawing shows a cross-section of a housing with various components labeled with numbers. On the left, a handle is attached to a shaft. The housing contains a central vertical plate with a slot. A horizontal plate with a circular hole is positioned above the slot. A rectangular component with a slot is located below the central plate. Various other parts are labeled with numbers 86, 87, 88, 89, 90, 91, 92, 93, 94, 95, 96, 97, 98, and 99. The drawing uses hatching and cross-hatching to indicate different materials or layers.

UNITED STATES PATENT OFFICE.

PETER WELIN, OF WORCESTER, MASSACHUSETTS, ASSIGNOR, BY MESNE ASSIGNMENTS,
TO LAWRENCE MAXWELL, OF CINCINNATI, OHIO.

AUTOMATIC COMBINATION SOLO MUSICAL INSTRUMENT.

1,136,385.

Specification of Letters Patent. Patented Apr. 20, 1915.

Application filed September 12, 1907. Serial No. 392,541.

To all whom it may concern:

Be it known that I, PETER WELIN, a citizen of the United States, residing at Worcester, in the county of Worcester and State 5 of Massachusetts, have invented a new and useful Automatic Combination Solo Musical Instrument, of which the following is a specification.

In order to operate pneumatically controlled musical instruments under either high or low air tensions as desired, two systems have been proposed heretofore, namely, the double bellows system as exemplified in a United States Patent 701,535 granted on 15 the 3rd day of June, 1902, jointly to Theodore P. Brown, and the present inventor, and the single bellows system in which the wind-chest is pneumatically divided either into treble and bass sections, or into a greater 20 number of sections. In the single bellows system it was necessary to operate the pedals with sufficient force to secure the loudest playing effects desired, even when all the 25 notes of one or several sections were modulated, as a high tension had to be produced and then cut down for modulation, and it was impossible to locate the point of change 30 from loud playing to low except at the points provided permanently in the construction of the instrument.

One of the objects of the present invention is to provide a system of operation and a construction for solo playing applicable 35 both to combination musical instruments and to separate players, in which when such variation is desired the ordinary playing will be done under low tension or pressure, and when it is desired to accent the notes the high tension or pressure can be connected with the operating pneumatics without a permanently divided wind-chest. In other words, the striking effect of the operating pneumatics is divided without a division of the wind-chest. This can be done 40 according to this invention with the employment of either the single or double bellows system.

Another object of the invention is to permit the change from one pressure or tension 45 to the other to be made at will between the sounding of any two notes.

This invention also comprises means whereby the accenting effect may be secured manually for the entire range of notes, and 50 means whereby it may be secured either

manually, or automatically by the control of the music-sheet as desired, for the entire range or for certain sections (as for example, octaves, thirds, etc.) thereof, and the provision of connections so arranged that if 60 a music sheet is used not wide enough to cover the extra tracker channels which must be provided in the latter case, they may very easily be rendered inoperative to produce any result.

All these objects preferably are attained by such means that they may be thrown out of operation so that the air tensions operating on the striking pneumatics will depend directly on the pumping, and the 701 operator may control the same at will.

In order to secure these results, this invention includes new and improved combinations and arrangements of parts throughout the entire pneumatic action, and in several of the elements thereof, in connection with which are certain improvements in the valve box for the striking pneumatics, other improvements in an invention made jointly by Hjalmar Utterberg and the present inventor and set forth in their joint patent on a regulating mechanism for automatic musical instruments, No. 999,281, patented Aug. 1, 1911, as well as in certain other features. This invention also comprises means for allowing the motor to race during the playing, this being desired in the performance of certain musical compositions.

Reference is to be had to the accompanying drawings which illustrate a preferred embodiment of the invention as applied to a combination player piano, in which—

Figure 1 is a diagrammatic view showing the main part of the pneumatic action. Fig. 2 is a front elevation of a portion of a combination piano showing one way in which this invention may be applied thereto. Fig. 3 is a plan of parts of the same showing a valve box, a sliding valve, and connections for operating the same and also illustrating a switch valve box and its connections. Fig. 4 is a plan of the switch valve box. Fig. 5 is a sectional view of the same on the line 5—5 of Fig. 4. Fig. 6 is a longitudinal vertical section of the valve box above referred to and of a portion of the governor box with a valve box therein showing the connections of said parts. Fig. 7 is a transverse sectional view of the valve box through one of the valves. Fig. 8 is a plan of the top 110

- plate of said valve box showing the slide valve. Fig. 9 is a plan of the same with the slide valve removed. Fig. 10 is a plan of a lower plate of the top of said valve box showing the passages controlled by the said slide valve. Fig. 11 is a bottom plan view of said slide valve. Figs. 12, 13, 14 and 15 are plans of certain of the more important plates of which the valve box is composed.
- 10 Fig. 16 is a plan of the governor box showing the upper part thereof in horizontal section. Fig. 17 is a plan of the same with the top plate thereof removed, parts appearing in section. Fig. 18 is a similar view showing the other end of the governor box. Fig. 19 is a sectional view on the line 19—19 of Fig. 17. Fig. 20 is a sectional view showing the tempo valve and its connection with the racing valve. Fig. 21 is a vertical longitudinal section of a valve box for the striking pneumatic, and a part of the channel board. Fig. 22 is a plan of one of the plates of said valve box showing the valves thereof. Fig. 23 is a plan of another one of said plates showing the pneumatics, and Fig. 24 is a plan of a lower plate showing the connection of the channels with said pneumatics and also illustrating in section the channel board.
- 20 30 While the invention is applicable to separate players for musical instruments it is perhaps more especially valuable in the combination pianos.
- For a general idea of the invention reference is to be had more especially to Fig. 1. In this figure the tracker-bar 10 is provided with the ordinary note channels 11 and with additional channels 12 which will hereafter be referred to as the accenting channels.
- 35 40 45 50 These channels 12 are shown as located at the ends of the tracker, but may be otherwise located as desired, and are of such size as to bring their front walls slightly in advance of those of the note channels, so that when a perforation in the music sheet, registering with one of these accenting channels, and in alinement with the note perforation or perforations which it is to control, comes into position to open it, the accenting arrangement will be set before the notes are struck.
- 55 60 65 Each of the note channels 11 is connected in the ordinary way through passages 13 with a pneumatic 14 located in a suction chamber 15. It is to be observed that while this invention is shown as applied to a double pneumatic operating system, it could be applied to any other system, as for example, a single pneumatic system. One of these suction chambers is shown as being provided for each of the striking pneumatics 16 and connected by channels 17 and 18 respectively with passages 19 and 20 which, as will be explained hereinafter, are connected with the low and high air tension
- chambers or chests respectively. Each passage 18 is connected with its suction chamber 15 through a port 21 which is normally closed by a valve 22 held down by a spring 23. Now when an air impulse passes through the passage 13 to lift the pneumatic 14 it raises a double valve 24—25 and cuts off a channel 26 from connection with the suction chamber, admitting the outer air to it. This lifts a secondary pneumatic 27 in a well understood manner so as to move a valve 28 to close an outlet port 29 and open a port 30 so as to allow the interior of the striking pneumatic 16 to communicate directly with the suction chamber 15, and cause the striking operation to take place influenced by the light air tension in the passage 19. This arrangement of primary and secondary valves and pneumatics is, of course, well understood in this art, and is merely shown here for the purpose of illustration as the invention may be used with any form of mechanism for accomplishing said results. Now when it is desired to accent a note or series of notes, air is admitted in one way or another to a channel 31 which, in this instance, communicates with a plurality of channels 32, each one entering a chamber 33 under a pneumatic 34 which operates the valve 22 of one of the striking pneumatic valve boxes to raise the same and cut off communication of the suction chamber 15 with the passage 19 and connect it with the passage 20. This produces high air tension in the suction chambers 15 which are in the series to be accented which are connected with the particular passage 31 which has been opened.
- 90 95 100 105 110 115 120 125 130 According to this invention there are several ways in which one or more of the channels 31 with which the instrument is provided, may be connected with the atmosphere to produce this result, namely, through the automatic control by the music sheet through the accenting channels 12, by a manually controlled slide valve controlling sections of the instrument, and by another manually controlled means which being connected with all the channels 31 operates simultaneously all the notes of the instrument.
- In order to secure control by sections, each of the channels 31 is connected with a suction chamber 330 through a port 340, and with the outer air through a port 35, these ports being controlled by a double valve 36—37 as is well understood. A pneumatic 38 controls the position of the double valve, and this is located in a chamber 39 which is connected by a passage 40 with one of the accenting tracker channels 12. Each chamber 39 is also connected through a channel 41 with an opening 42 which openings are controlled by a slide valve 43 operated manually as will be described herein-

after, and having a notch 44 for uncovering the openings 42.

It will be understood that there is a channel 40 and a channel 41 as well as a chamber 39 for each channel 31; that is, if the instrument is divided into six sections, there will be six of these channels or passages, and each accenting channel 12 of the track-bar will control one of the sections of actions.

When it is desired to connect the parts so that the entire instrument is operated under heavy air tensions, a manually operated valve 45 is employed. This valve is shown as being controlled by the lever 46, the operation of which has been described in this inventor's co-pending application for patent on a pneumatically controlled music playing device, filed Feb. 5, 1907, Serial No. 355,863, and the details of which are not claimed in this application. The depression of this lever, as has been described in my above identified application, admits air into a plurality of passages 47, one of which is connected with each of the passages 41 or 40 so as simultaneously to operate all the pneumatics 38.

Referring back to the suction chamber 330, it will be seen that instead of the usual primary and secondary valve employed for preventing the connection of the suction chamber with the outer air for any considerable length of time, I have provided means for preventing such a connection, and for permitting the use of the device without any secondary valve. With the chamber 39, or preferably with the passages 40 and 41 is connected a passage 48 which extends into a chamber 49 over which is a pneumatic 50 provided with a valve 51 normally held down by a spring 52 if desired. This valve is for closing a port 53 connecting the suction chamber through a restricted bleed passage 54 with the chambers 39 and 49 which are in communication with each other. Now when an air impulse passes through any of the passages 40, 41 or 47, it will enter the chamber 49 and lift the pneumatic 50. As this pneumatic does not lift against any air pressure, the chamber 49 and the passage 54 being connected with the suction chamber at this time, and as the valve 37 does lift against the air pressure, and is of a heavier weight, the first action of the impulse of air is to close the valve 51, so as to prevent bleeding of atmospheric air into the chamber 330 through the port 53 during the operation of the pneumatic 38. It will be understood that the passage 48 is not an absolute necessity. The passages 40, 41 and 47 communicate with the chambers 39 and 49, in any desired way. They are shown as opening into a passage 48 communicating with them. It is preferred to conduct the air into the chamber 49

through the separate passage 48 so that there will be no force to operate the pneumatic 38 before the pneumatic 50 rises.

The slide valve 43 is employed for a purpose additional to that stated. In the position indicated in Fig. 1, it covers a port 55 which communicates through a passage 56 with a chamber 57. This passage communicates with a chamber 58 and through a restricted passage 59 and port 60 with a suction chamber 61. The passage 56 is shown as communicating with the chamber 58 through an additional passage 62, which gives the same results as a direct connection. In the chambers 57 and 58 are pneumatics 63 and 64. The pneumatic 63 controls a valve 65 which controls ports 66, one connecting a collapsible pneumatic 67 with the suction chamber, and the other with the outer air. The operation of this pneumatic and valve will be obvious. The pneumatic 64 supports a valve 68 preferably held down by a spring 69 which controls the port 60 and operates like the valve 51 above described.

It is to be observed that the operation of the device as described above is such as takes place when the sliding valve 43 is in such position as to uncover the port 55. In the position in which this valve is shown in Fig. 1, this port is closed, and the passages 19 and 20 are both under high tension as will be explained hereinafter. In this case the function of the pneumatic 67 when inflated is to operate an arm 70 to hold a slide valve 71 open so as to uncover a port or ports 72. A high air tension chamber 73 located in a governor box is communicating through a passage 74 (Fig. 19) with a high air tension storor or reservoir, not shown in Fig. 1. These ports 72 connect the chamber 73 with a chamber 75 which is connected with the chamber 61 by a passage 76. The governor box is also provided with a chamber 77 which communicates directly with the chamber 75 and additionally communicates with the chamber 73 through a passage 78 which is automatically regulated by a diaphragm operating the valve 79, the closing action of which may be regulated. These chambers, as so far indicated are substantially the same as set forth in the above described joint patent of the present inventor and Hjalmar Utterberg, but in that case the valve 71 is not shown as operated mechanically or pneumatically as in the present case.

The chamber 73 is adapted to be connected with a chamber 80 which communicates through ports 800 (Fig. 16) with the high air tension passage 20. The chamber 73 also communicates with a chamber 81 which opens through a port 82 in a partition into a chamber 83 communicating directly with the motor through a passage 84. Conse-

5 quently it will be seen that a high air tension is always present in the chamber 81 and that it can be put into communication with the motor, and also when the valve 71 is open, the chamber 77 is also in direct communication with the source of high air tension. The latter chamber communicates through ports 85 and 86 with the passage 19. The chambers 73 and 80 may be connected through passages 87 by a hollow valve 870.

10 Now when it is desired to operate the instrument as above described, the valve 43 is moved so as to uncover the port 55, collapse the pneumatic 67, and close the ports 72. Then the only communication between the chamber 73 and the chamber 75 is through the port 78 which is controlled by the regulator diaphragm. Consequently, a lower air 15 tension will be provided in the chamber 77 and the instrument can be operated as stated, it being understood that the port 55 remains open during all the time during which such operation takes place, and when it is closed, 20 there will be only one air tension and the striking blows of the pneumatic will be regulated by the pumping alone, which, however, is not the normal way of operating the instrument.

25 30 In further explanation of Fig. 1, it may be stated that the chamber 81 communicates through a passage 88 with a chamber 89, and that the passage 88 is controlled by a diaphragm 90 operating a throttle valve (not shown) in the same way that the passage 78 is controlled. The chamber 89 communicates with the chamber 83 through a graduated opening 91 controlled by the tempo valve 92 so as to supply air to the motor 35 under ordinary conditions so as to be controlled at will by the tempo valve.

40 It will be noticed that the port 82 is controlled by a valve 93 which is ordinarily closed during playing, and that the ports 85 45 are controlled by a valve 94 on the same valve stem these valves being so located that one is closed when the other is open. Also the valve 870 is mounted on the same valve stem and disconnects the chambers 73 and 80 50 when rewinding. Therefore, when playing with the port 55 open valves 94 and 870 open and valve 93 closed air is exhausted from the motor through the automatically controlled passage 88 and the graduated passage 91 55 controlled by the tempo valve. Now when is desired to reroll the sheet, the valves 93, 94 and 870 are shifted, which shuts off the chamber 80 and passages 85 from all the sources of air tension, so as to prevent any 60 sounding of the notes by the low air tension. As the chamber 330 is connected with the chamber 80 through a passage 96, the former also becomes dead at this time and the valve 22 cannot be operated to connect the suction 65 chambers 15 with the high air tension pas-

sage 20. There is always free connection between the chambers 73 and 81 to operate the motor. It will be seen that there is another port 97 from the chamber 81 to the chamber 83, normally closed by a valve 98. 70 Now when it is desired to cause the motor to race during playing, as has been found of advantage in the rendering of certain musical compositions, this valve is opened and the high tension is brought directly into the 75 motor without any regulation whatever. This is done by pushing the tempo valve beyond its range which through a valve stem 99 opens the valve 98.

80 It will be observed that the features just described relate in part to the above described joint patent of this inventor and Hjalmar Utterberg, but contain certain improvements over the same.

85 In several instances in the above description of Fig. 1, channels, chambers, tubes, etc., have been referred to broadly as passages and it is intended that where this has been done, the numerals applying to such passages shall designate the passages in their 90 entirety even when composed in part of one of these elements, and in part of others. In the detailed description of the drawings hereinafter given, such passages will again be referred to in some cases and their component parts numbered.

95 Reference is to be had to the other figures of the drawing for a more detailed disclosure of a simple construction embodying the features of the invention set forth broadly 100 above including some additional features not shown in Fig. 1.

105 Referring especially to Figs. 2 and 3, it will be seen that the slide valve 43 is mounted on a valve box 100 located adjacent to a tracker-box 101 which is shown as of the general form indicated in this applicant's above mentioned application and will not be described herein in detail. It of course contains the tracker 10 and tubes connecting and 110 forming part of the passages 13 and 40. It also is provided with a scale 110 which moves the pointer 111 connected with the rod 112 which is connected with the rock-shaft 113 operated by a lever 114. Connected also with the rock-shaft is an arm 115 operating through a link 116 and lever 117 which is connected by a link 118 with the slide valve 43. The operation of these parts 115 will be readily understood. In the tracker box also, is located a handle 120 connected directly with a slide valve 121 which as shown more clearly in Fig. 6, has a series of 120 passages 122 adapted to connect two series of chambers 123 and 124 with each other or disconnect them, according to the position of this slide valve. These channels 123 are connected with tubes 125 which form a part 125 of the passages 40. The chambers 123 and 124 constitute a part of the passages 40. 130

Consequently, when it is desired to play with paper not extending over the tracker-channels 12, that is, paper not especially prepared for such a tracker, this slide valve is operated by means of the handle 120 so as to close the passages 40. This feature is shown and claimed in my above identified application and consequently is illustrated herein only to show its connection with the rest of the apparatus.

The lever 46, valve 45, and passage 47 have been referred to before. The passages 47 six in number in the form shown, all terminate in ports 127 which are closed by the valve 45 which is normally held up by a spring 129. These elements are mounted in a valve-box 130 and operated as has been stated and as is more particularly set forth in my above identified application.

The valve box 100 and the operation of the sliding valve 43 will now be described. As has been stated, the valve box is provided with a port or slot 55 and a plurality of ports 42, these being located in the top-plate 131 of the valve box on which the valve slides. This valve instead of having the complications set forth in my above identified application, is preferably made solid and of aluminum or other suitable material.

The notch 44 with which it is provided is the only irregularity in its surface. The slot 55 and the ports 42 are so located that the valve can cover them in such position that the notch 44 will not open any of the ports 42 as is indicated in Fig. 8. This is the position of this valve when the instrument is to be played in the old way, before accenting and modulating arrangements were in common use; that is, when it was desired to secure the variations in the striking effects by variations in the pumping. This, however, is not the way in which this instrument is intended to be operated ordinarily.

For ordinary playing the valve is moved sufficiently to the left in Fig. 8 to uncover the end of the slot 55 so as to throw the instrument on to the low air tension passage. This is the position for what is termed "normal playing," and in this position the exhaust chambers 15 are connected with the low air tension passage 19. While playing in this way if it is desired to accent any section of actions, the valve is shifted so that the notch 44 will uncover one or more of the ports 42, the port 55 remaining open. It will be understood that while this instrument is illustrated as having six of these ports, any desired number may be employed. One may be employed for each individual striking pneumatic if desired, but in practice as no two adjacent keys are ever struck, one lightly and the other with a heavy blow, to produce a chord or a part of a chord, all the desired variations can be secured by ar-

ranging the striking pneumatics in sets of three, and when this is done the number of ports 42 will be equal to one-third of the keys of the instrument. However in the present case the instrument is shown as being divided up into only six sections.

In the form shown the valve box 100 is constructed as follows: Below the top-plate of the valve box is a plate 133 having channels communicating with the slot 55 and the ports 42 and constituting a part of the passages 56 and 41 respectively. Below this is another plate 134 in which the channels constituting continuations of said passages are all located near one side of the plate and open into a block 135 through which they continue downward into a plate 136. The upper three plates above described are supported at a distance from the plate 136 by posts 137, and the space constitutes an outlet to the open air from a chamber below as will be described. This plate 136 in addition to the channels which have been followed down to this point, contains a number of sets of ports 35 which have been referred to heretofore, equal to this number of ports 42. Below this plate is a plate 138 containing, as before, continuations of the passages 56 and 41, and also containing a series of channels 139 located between the several ports 340 and 35. This plate also contains channels constituting part of the passages 31 opening from the several chambers 139. The next plate 140 contains continuations of all the above mentioned channels, and below it a plate 141 is provided in which is located the vacuum chamber 330. This plate, of course, contains continuations of the passages 31, 41 and 56, and in addition thereto the bleeding channels 54 in which are located disks 142 provided with pin-hole openings through which the bleeding action takes place. In this plate also are secured centrally perforated disks 143 which contain the ports 53. The next plate 144 contains continuations of the passages 31, 41 and 56, and also the chambers 39 and 49 on which are mounted the pneumatics 38 and 50. This plate extends past the end of the upper plates and furnishes a base for the reciprocation of the valve 121. It also contains the ends of the passages 123 and 124 which are connected by said valve, and on it is provided a block 145 into which the ends of the tubes 125 extend, these tubes communicating with the channels 123 which extend through this plate. The next plate 146 contains continuations of the channels 123 and 124, and of the passages 31, 41 and 56 and channels constituting part of the passages 47, these channels leading into the chambers 49 as has been stated. It is in this plate that the several channels constituting part of the passages 40, 41 and 47 are preferably connected. Below this a plate 147 is mounted in which

the passages 31, 96, 56 and 47 are continued, and the valve box terminates in a bottom plate 148 in which these various passages are connected at the end with a block 150 5 through which they pass to a plate 151 in which they are connected through the various tubes with the other parts of the apparatus. On this plate 151 is a block 152 through which the tubes constituting a part 10 of the passages 13 from the note channels of the tracker bar are connected and by which they are supported. These latter tubes extend to the channel-board 154, extending 15 through the same without communicating with the interior thereof, and terminating under the pneumatics 14 as has been set forth. This is indicated in Fig. 24. The tubes constituting part of the channels 31 also extend into this channel-board and 20 there each one communicates with a plurality of channels 32.

The channel board is made up of a plurality of plates. The outside plate 155 has 25 passages for the tubes as above described, and passages for tubes which constitute part 30 of the passages 31. The next plate 156 is spaced from the plate 155 by blocks 157 forming channels constituting continuations 35 of the passages 31 communicating in the plate 156 with passages 32. The next plate 158 is spaced from the plate 156 by blocks 157 forming channels designated as 20 which 40 communicate with the passages 18 extending through said plate 158. Another set of blocks 159 form channels 19 communicating with passages 17 extending through the last plate 160, and communicating with the several suction chambers 15. The plate 151 is applied so as to cover the open ends of the 45 passages 17 and 18, tubes 18 and 32 extending into them through the channel-board.

In Fig. 6 is shown a tube constituting part 50 of a passage 56 extending into a valve box 170. This valve box is mounted on the top 55 of the governor box which has been mentioned, and it is thought that it has been sufficiently described above. It is shown as comprising three plates, but may be made in any desired way. At this point may be observed 60 that a spring 171 is applied to the lever 70 to assist in opening the pneumatic 67 and the valves 71.

The striking valve box shown in Figs. 21, 55 22, 23 and 24 has been sufficiently described in connection with the description of Fig. 1, and it is thought unnecessary to go into the details of the construction of the same, as it is the general combination which it is desired to claim herein. One of these valve 60 boxes is provided for each striking pneumatic, and they are attached to the channel-board as is indicated in the first of the above mentioned figures. Each one is preferably made up of a series of plates in a manner

which is well-known, and which will need 65 no description.

The channel 26 which has been referred to above and which is not shown in my above mentioned application, is shown in these figures as consisting of a series of passages 70 through the different plates of the valve box. The arrangement of the valves is shown in the same way as in the diagrammatic view; that is, the valve 28 and its pneumatic 27 are located between the valves 22 and 24, but 75 this arrangement may be varied as may be found convenient.

While only one embodiment of this invention is herein illustrated and described and it is shown as applied to an upright combination or player piano, it is to be understood that many modifications may be made therein by any person skilled in the art, and that the invention may be applied to piano players and other instruments without departing 85 from the scope of this invention as expressed in the claims. Therefore, I do not wish to be limited to the particular form shown, but 90

What I do claim is:—

1. A music playing action having a plurality of striking pneumatics, a chamber for each of said pneumatics, a passage for high air tensions or pressures, a passage for low air tensions or pressures, yielding means in the action for normally connecting the last 95 named passage with said chambers, and means in the action for cutting off a plurality of said chambers from the low air tension passage and simultaneously connecting them with the high air tension passage. 100

2. A music playing action having a plurality of striking pneumatics, a chamber for each of said pneumatics, a passage for high air tensions or pressures, a passage for low air tensions or pressures adapted to be connected with said chambers for operating said pneumatics, means in the action for cutting off a plurality of said chambers from the low air tension passage and connecting them with the high air tension passage, and 110 a slide valve controlling said means for cutting off a plurality of said chambers from the low air tension passage in succession as the valve moves in one direction, and simultaneously connecting them with the high 115 air tension passage.

3. In a music playing device, the combination with a plurality of elements, a striking pneumatic in each element and an air chamber for each of said pneumatics, of a 120 passage for high air tensions or pressures, a passage for low air tensions or pressures both extending into each element and connected with all of said chambers, and means in each element for cutting off its chamber 125 from the low air tension passage and connecting it with the high air tension passage.

4. In a music playing device, the combi-

- nation with a plurality of striking pneumatics and a chamber for each of said pneumatics, of a channel board having a passage for high air tensions or pressures and a passage for low air tensions or pressures adapted to be connected with said chambers for operating said pneumatics, manually controlled pneumatic means in the action for cutting off all of said chambers from the low air tension passage, a manually operated valve controlling said means for cutting off a plurality of chambers from the low air tension passage and connecting them with the high air tension passage, and a governor connected with the low air tension passage, whereby the governor will be ineffective during accenting.
5. In a music playing device, the combination with an action comprising a plurality of striking pneumatics, a chamber for each of said pneumatics, a passage for high air tensions or pressures, and a passage for low air tensions or pressures adapted to be connected with said chambers for operating said pneumatics, of a manually controlled slide valve for cutting off all said chambers from the low air tension passage one after the other, as the valve moves in one direction and simultaneously connecting them with the high air tension passage, and a valve box comprising means constituting part of the action for cutting off a section or sections of chambers from the low air tension passage and connecting them with the high air tension passage controlled from the tracker.
6. In a music playing device, the combination with a tracker, of an action comprising a plurality of striking pneumatics, a chamber for each of said pneumatics, a passage for high air tensions or pressures, and a passage for low air tensions or pressures adapted to be connected with said chambers for operating said pneumatics, manually controlled pneumatic means for cutting off all of said chambers from the low air tension passage and connecting them with the high air tension passage, a manually operated valve controlling said means for cutting off a plurality of sections of chambers from the low air tension passage and connecting them with the high air tension passage, and a valve box constituting part of the action for cutting off a section or sections of chambers from the low air tension passage and connecting them with the high air tension passage and for controlling said low air tension passage.
7. In a music playing device, the combination with a plurality of striking pneumatics and a chamber for each of said pneumatics, of a passage for high air tensions or pressures, a passage for low air tensions or pressures normally connected with said chambers for operating said pneumatics, a plurality of means for cutting off the chambers from the low air tension passage and connecting them with the high air tension passage, and a valve box provided with a passage and connections for controlling said low air tension passage and with a plurality of passages, each for controlling one of said means for cutting suction chambers off from the low air tension passage.
8. In a music playing device, the combination with a striking pneumatic and a chamber, of a passage for high air tensions or pressures, a passage for low air tensions or pressures connected with said chamber for operating said pneumatic, means for cutting off the chamber from the low air tension passage and connecting it with the high air tension passage, and a valve box having a port and connections for controlling said low air tension passage, and a port for controlling said means for cutting off the suction chamber from the low air tension passage.
9. In a music playing device, the combination with a striking pneumatic and a chamber, of a passage for high air tensions or pressures, a passage for low air tensions or pressures connected with said chamber for operating said pneumatic, means for cutting off the chamber from the low air tension passage and connecting it with the high air tension passage, a valve box having a normally open port and connections for controlling said low air tension passage, and a port and connections for controlling said means for cutting off the suction chamber from the low air tension passage, and a valve adapted to cover both of said ports when moved to a certain position and to uncover the first port whenever it uncovers the second port.
10. In a music playing device, the combination with a plurality of striking pneumatics and a chamber connected with each of said pneumatics, of a passage for high air tensions or pressures, a passage for low air tensions or pressures connected with said chambers for operating said pneumatics, means for cutting off the chambers from the low air tension passage and connecting them with the high air tension passage, a valve box having a surface provided with a port and connections for supplying said low air tension passage with a low air tension when said port is open, and with a plurality of ports, a plurality of passages, each connected with one of said plurality of ports for controlling said means for cutting a suction chamber off from the low air tension passage, and a valve adapted to cover all of said ports and having a notch for opening one or more of said plurality of ports, said notch being so located that whenever any of the said plurality of ports is open, the first named port will also be open.
11. In a music playing device, the combi-

5 nation with a striking pneumatic and a suction chamber therefor, of a high air tension passage, a low air tension passage, a valve box having a port, connections controlled by
 10 said port for supplying said low air tension passage with a low air tension when said port is open, said suction chamber being connected with the low air tension passage, said box having a second port, means for connecting the suction chamber with the high air tension passage when said second port is open, and a valve for said ports, said valve being arranged to uncover the first of said ports before it uncovers the second and to
 15 keep it uncovered whenever said second port is open.

12. In a music playing device, the combination with the striking pneumatics, chambers connected therewith for operating them, a low air tension passage, a high air tension passage, a valve for controlling the connection of each of said chambers with said passages, a valve box having a series of ports and passages for controlling said valves and
 20 a port having connections for preventing the admission of high air tension or pressure to said low air tension passage, and a valve for controlling said ports.

13. In a music playing device, the combination with the striking pneumatics, suction chambers connected therewith for operating them, a low air tension passage, a high air tension passage, a valve for controlling the connection of each of said chambers with
 30 said passages, a valve box having a series of ports and passages for controlling said valves, and a port having connections for preventing the admission of high air tension to said low air tension passage, and a valve for controlling said ports, said valve having means for opening certain of said series of ports when moved to a certain position and being so located as to always open the last named port when any one of said series of
 40 45 ports is opened.

14. In a music playing device, the combination with striking pneumatics, of a valve box having a channel therein terminating in a port, a series of channels therein terminating in a corresponding series of ports, a valve for covering said ports, said valve having a notch for opening one or more of said series of ports, said notch being so located with respect to the end of the valve
 50 55 that the first named port will be opened before said notch opens any of said series of ports, and will continue open during all the time when any of said series of ports are open, means connected with the series of ports for controlling the supply of the several striking pneumatics with high air tension, and means controlled from the first named port and channel for the supply of the striking pneumatics with low air tension.

15. In a music playing device, the combination of a striking pneumatic, a valve box with which said pneumatic is connected, said valve box having a suction chamber, a high air tension passage, a low air tension passage, channels connecting said suction chamber with both of said passages, a valve for controlling said channels, a spring for holding said valve in position to close the channel connected with the high air tension passage, a pneumatic for changing the position of said valve to open the channel connected with the high air tension passage and close the channel connected with the low air tension passage, a valve box having a channel provided with connections for controlling said low air tension passage to maintain a low air tension therein and channels having connections for operating said pneumatics when the channels are open, and a valve for controlling said channels.

16. In a music playing device, the combination of striking pneumatics, suction chambers therefor, a high air tension passage, a low air tension passage, channels connecting each of said suction chambers with both of said passages, valves for controlling said channels, springs for holding said valves in position to close the channels connected with the high air tension passage, pneumatics for changing the position of said valves to open the channels connected with the high air tension passage and close the channels connected with the low air tension passage, a channel provided with connections for controlling said low air tension passage to maintain a low air tension therein, a series of channels arranged in order having connections for operating said pneumatics when said channels are open, and a valve for controlling the last named channels, said valve having means whereby the first of said channels is always open when any one or more of the series of channels is opened by the valve, whereby the opening of the first mentioned channel will connect the suction chambers with the low air tension passage, and the opening of any of the series of channels will connect one or more of the suction chambers with the high air tension passage.

17. In a music playing device, the combination of a striking pneumatic, a suction chamber therefor, a high air tension passage, a low air tension passage, channels connecting said suction chamber with both of said passages, a valve for controlling said channels, means for holding said valve in position to close the channel connected with the high air tension passage, a pneumatic for changing the position of said valve to open the channel connected with the high air tension passage and close the channel connected with the low air tension passage,

a channel provided with connections for controlling said low air tension passage to maintain a low air tension therein, a channel having connections for operating the 5 said pneumatic when the channel is open, a valve for controlling said channels, and means whereby when said valve closes both of said channels the low air tension passage will be connected with the high air tension 10 passage.

18. In a music playing device, the combination of a striking pneumatic, a suction chamber therefor, a high air tension passage, a low air tension passage, both leading 15 directly to the suction chamber, means for connecting said suction chamber with said passages, a passage having connections controlled thereby for supplying said low air tension passage with a low air tension when 20 said passage is open, and when closed for connecting said low air tension passage directly with the high air tension passage.

19. In a music playing device, the combination with a tracker, a plurality of striking pneumatics and a chamber connected with each of said pneumatics, of a passage 25 for high air tensions or pressures, a passage for low air tensions or pressures adapted to be connected with said chambers for 30 operating said pneumatics, manually controlled pneumatic means comprising valves in said chambers for cutting off all of said chambers from the low air tension passage and connecting them with the high air tension 35 passage, automatically operated pneumatic means operating upon said valves for cutting off a section or sections of chambers from the low air tension passage and connecting them with a high air tension passage 40 controlled from the tracker, and means for cutting off the connection of the tracker with said pneumatic means.

20. In a music playing device, the combination with a tracker, a plurality of striking 45 pneumatics and a chamber connected with each of said pneumatics, of a passage for high air tensions or pressures, an independent passage for low air tensions or pressures normally connected with said chambers for operating said pneumatics, means for cutting off the chambers from the 50 low air tension passage and connecting them with the high air tension passage, said means comprising a valve in each chamber a manually operated controlling device and an 55 automatically operated controlling device controlled from the tracker for operating the valves, and manually operated means for cutting off the connection of the tracker 60 with said automatic controlling device.

21. In a music playing device, the combination with a striking pneumatic, a suction chamber therefor, two passages having different air tensions, each connected with

said suction chamber, a valve for controlling 65 the connection of said passages with the suction chamber, a pneumatic for operating said valve, a passage connected with said pneumatic for operating it, a valve for controlling the last named passage, a pneumatic 70 for operating the last named valve, a suction chamber with which the latter pneumatic is connected, a passage for controlling the operation of said last named pneumatic, a restricted connection between the last 75 named passage and the last named suction chamber, a valve for closing said connection, and a pneumatic for operating the last named valve and communicating with the last named passage. 80

22. The combination with a striking pneumatic, connections for operating said pneumatic, a valve for controlling said connections, a pneumatic for operating said valve, a suction chamber, a passage from said suction chamber to said pneumatic, a second valve for controlling said passage, a pneumatic in the suction chamber for operating said second valve, a second pneumatic in said suction chamber, a valve supported by 90 the last named pneumatic, a restricted passage adapted to be closed by said valve, and a channel communicating with the last named two pneumatic and with said restricted passage. 95

23. The combination with a striking pneumatic, connections for operating said pneumatic, a valve for controlling said connections, a pneumatic for operating said valve, a suction chamber, a passage from said suction chamber to said pneumatic, a second valve for controlling said passage, a pneumatic in the suction chamber for operating said second valve, a second pneumatic in said suction chamber, a valve supported by the last named pneumatic, a restricted passage adapted to be closed by said valve, a channel communicating with the last named two pneumatics and with said restricted passage, the last named valve being adapted to close 110 without atmospheric pressure behind it, and the second valve being adapted to close against atmospheric air pressure whereby the last named valve will close before the second valve and shut off the suction chamber from said passage before the second valve operates to disconnect the first pneumatic from the suction chamber. 115

24. In a music playing device, the combination with striking pneumatics, of an accenting device adapted to control a plurality of said striking pneumatics, a governor box having a chamber for high air tensions and a chamber for low air tensions, a valve for preventing direct connection between said chambers, means for operating said valve in the governor box, a pneumatic, a passage for admitting air under said pneu- 120 125

matic to operate the same, a suction chamber with which said pneumatic is connected adapted to communicate with one of the chambers in said governor box, a second 5 pneumatic in said suction chamber, a valve supported by the second pneumatic, and a restricted passage adapted to be controlled by said valve and extending from the suction chamber into communication with the 10 other side of both of said pneumatics.

25. In a music playing device, the combination with a striking pneumatic, of an accenting device therefor, a governor box having a chamber for high air tensions and a 15 chamber for low air tensions, a valve for preventing direct connection between said chambers, means for operating said valve in the governor box, a pneumatic, a passage for admitting air under said pneumatic to 20 operate the same, a suction chamber with which said pneumatic is connected adapted to communicate with one of the chambers in said governor box, a second pneumatic in said suction chamber, a valve supported by 25 the second pneumatic, a restricted passage adapted to be controlled by said valve and extending from the suction chamber into communication with the other side of both of said pneumatics, said second pneumatic 30 being adapted to operate under lighter pressure than the first pneumatic, whereby said valve will be closed before the first pneumatic operates and the suction chamber will be cut off from communication with the 35 other side of said pneumatics before the first pneumatic operates.

26. In a music playing device, the combination of a governor box having a low air tension chamber and a high air tension 40 chamber, a valve for controlling direct communication between said chambers, a suction chamber, a channel adapted to open to the air, a pneumatic connected with said channel and communicating with said suction chamber connections for controlling the 45 operation of said valve, and means for closing connection between said channel and suction chamber before said pneumatic operates.

50 27. In a music playing device, the combination of a main chamber connected with a source of air tension or pressure, a low tension chamber, a passage connecting said chambers, means for cutting down the air 55 tension or pressure in said passage, a direct connection between said chambers, a valve for controlling said direct connection, means for operating said valve, a third chamber, means for providing a direct connection be- 60 tween the first chamber and the third chamber when desired, a high air tension passage connected with the third chamber, a low air tension passage connected with the second chamber, striking pneumatics, and means

for connecting said passages with said striking pneumatics for operating them. 65

28. In a music playing device, the combination of a main chamber connected with a source of air tension or pressure, a low tension chamber, a passage connecting said chambers, means for cutting down the air tension or pressure in said passage, a direct connection between said chambers, a valve for controlling said direct connection, means for operating said valve, a third chamber, 70 means for providing a direct connection between the first chamber and the third chamber when desired, a passage connected with the third chamber, a passage connected with the second chamber, striking pneumatics, 75 and means for connecting said passages for said striking pneumatics for operating them, a fourth chamber, a direct and constantly open connection between the first chamber and the fourth chamber, and means for connecting the fourth chamber with the motor 80 for operating the same. 85

29. In a music playing device, the combination of a main chamber connected with a source of air tension or pressure, a second 90 chamber connected through a regulated passage with the first chamber, a third chamber connected with the first chamber, a valve adapted to open and close the connection between the first and third chambers, a motor 95 chamber for direct connection with a motor, a valve for opening a direct connection from the first chamber to the motor chamber, a passage connected with the second chamber, a passage connected with the third chamber, 100 striking pneumatics adapted to be connected with either of said passages so as to operate under high or low tension, a valve for controlling the connection of the second chamber with said passage connected therewith, 105 and means for moving said three valves simultaneously so as to close the connection between the first and third chambers and between the second chamber and its passage, and to open the connection between the first 110 chamber and the motor chamber for rewinding. 115

30. In a music playing device, the combination of a chamber connected with a source of air tension or pressure, a motor chamber 115 adapted to be connected with the first chamber, a tempo valve for controlling the flow of air between the motor chamber and the first named chamber, a racing valve adapted to open a free connection between the 120 said chambers while the instrument is being played, and means connected with the tempo valve for opening said racing valve when the tempo valve moves in a position to accelerate the motor in the forward direction to the maximum extent during playing. 125

31. In a music playing device, the combination with a motor and tempo valve for

manually controlling the speed of the motor, of means separate from the tempo valve whereby, when the tempo valve is being opened during playing, the opening there-
5 of to its fullest extent only will cause the motor to operate at maximum speed.

In testimony whereof I have hereunto set

my hand, in the presence of two subscr-
ibing witnesses.

PETER WELIN.
